DRILL CLEANING APPARATUS

Otto E. Schiffner, Nevada City, Calif.

Application May 18, 1934, Serial No. 726,329

12 Claims. (Cl. 15—94)

My invention relates to drill cleaning apparatus, and more particularly to an apparatus or device for effecting cleaning of hollow drills of the type generally employed as rock drills in mines, quarries, and analogous places.

Introduction

Hollow drills of the character described generally comprise an elongated stem member terminating in a winged drill bit. A passage is formed within the stem and leads through the end of the drill bit. In operation, a cooling fluid, such as water, is conducted through the passage to perform the double function of preventing overheating of the drill and of washing away drillings which tend to accumulate in the passage. It frequently happens during operation, that the passage becomes clogged by rock dust or other foreign matter, particularly when the drill is operating in ground containing clay. When clogging occurs, it then becomes necessary to clean the passage for further use of the drill.

Heretofore, various methods have been utilized for effecting cleaning of a clogged drill passage. One of these methods was to employ a tool, such as a hammer, and strike the drill therewith. This method will not dislodge tightly packed material. Resort has also been taken to drilling out a clogged drill passage or core with another drill. Such method is obviously slow and impractical due to the length of the drill and the small diameter of the drill passage.

Objects of invention

My invention is designed to obviate the foregoing described difficulties; and it is, therefore, an object of my invention to provide improved means for effecting cleaning of drills of the character described.

Another object of my invention is the provision of improved drill cleaning means, in the form of an apparatus of simple and economical construction.

Another object of my invention is the provision of a drill cleaning apparatus which will operate to clean drills efficaciously and rapidly.

Other objects of the invention will become apparent from a perusal of the following description thereof.

General description

In general terms, the apparatus of my invention comprises means for supporting the drill for movement, together with means for impart-

ing rapid successive impacts to the drill so as to cause vibration thereof. Preferably, the impacts are effected by a rapidly vibrating hammer member which strikes against a dolly or supporting member for an end of the drill. Although mechanical means can be employed for vibrating the hammer, it is preferred to utilize a fluid pressure operated hammer and to pass some of the fluid under pressure into the passage of the drill while it is being vibrated, so as to cooperate in removing the clogged material.

Description of drawing

Reference will now be made to the drawing for a more detailed description of the invention. In the drawing:

Figure 1 is a front sectional elevation of the apparatus of my invention; the drill being shown mounted on the apparatus.

Figure 2 is a side elevation of the apparatus, and illustrates in dotted lines a swung away position of the drill supporting cylinder or tube forming part of the apparatus.

Figure 3 is a vertical sectional view of a piston or anvil mounted for cushioned slidable movement in the cylinder or tube of the apparatus, and illustrates a portion of the upper end of a drill in position in the anvil.

Figure 4 is a vertical sectional view of a portion of the drill cylinder or tube, illustrating a modified form of means for cushioning the movement of the drill anvil.

Figure 5 is a top perspective view of the drill bit supporting member, or dolly, illustrating the cross slots therein for receiving the drill bit wings.

Detailed description

As can be seen from Figures 1 and 3, the type of drill which the apparatus of my invention is adapted to clean comprises a stem 1 having passage 2 therethrough for conveying cooling fluid to the drill bit or end 3 having drill wings 4 extending transversely with respect to each other; it being, of course, understood that the specific drill construction depicted is merely chosen for purposes of illustration, as the apparatus of my invention can be employed for cleaning any type of hollow drill or any other hollow member having a passage which is apt to become clogged.

The apparatus or drill cleaning device, in its preferred form, comprises a supporting frame or base 6 having spaced U-bolts 7 secured thereto in which is pivotally mounted T-pipe 8 sealed

at end 9 thereof. Opposite end 11 of T-pipe 8 has any suitable type of sealed journaled connection with pipe 12 connected to any suitable source of fluid pressure supply for a purpose to be subsequently described. A pipe or cylinder 13, providing a tube, is connected to the stem of T-pipe 8; and because of the pivotal mounting of T-pipe 8, it is apparent that cylinder 13 is mounted for swinging movement relative to base 6. When the apparatus is in operation, cylinder 13 is held against movement by spring latch 14 of any suitable construction.

Cylinder 13 has anvil or piston 16 slidably mounted therein, of cylindrical shape and having in its under end recess 17 to receive the upper end of drill stem 1. To facilitate proper guiding and alinement of the drill stem in recess 17, a portion 18 thereof is flared outwardly. A small-diameter passage 19 extends through the anvil from the dished top 21 thereof to recess 17; and packing rings 22, of suitable packing material, are seated in the outer surface of anvil 16 to provide a fluid tight piston fit with the inner wall of cylinder 13. In operation, as will be subsequently explained, fluid under pressure is introduced into cylinder 13; and to insure a tight fit of packings 22 with cylinder 13, radial holes 23 are formed in the anvil to communicate, from points adjacent the packings 22, with passage 19. This permits the fluid to exert direct pressure against the packings.

At the lower end thereof, cylinder 13 has apertured drill alining cap 24 screw threaded thereon. When it is desired to insert a drill stem into the cylinder for engagement in recess 17 of anvil 16, latch 14 is released and cylinder 13 is swung away from base 6. The aperture in cap 24 directs proper entrance of the drill into cylinder 13. Removal of the drill is performed in a similar manner.

From the preceding description, it is seen that the upper end of the drill is adapted to be engaged in slidably mounted anvil 16. The lower edges of the wings 4 of the drill bit 3 are adapted for support in cross slots 26 shaped to conform to the wing edges and located in the top of dolly 27. Dolly 27 has a shoulder 28 resting freely on the top of a pneumatic hammer 29 of any conventional construction and of the type in which the hammer proper is caused to reciprocate by pneumatic pressure. Also, dolly 27 has a passage 31 leading from the top thereof to the side, and which communicates with passage 2 of the drill when supported on the dolly. Piston or hammer member 32 is slidably mounted in pneumatic device 29; and, under pneumatic pressure, hammer 32 strikes intermittently against stem 33 of dolly 27 to cause vibration of the dolly and thereby cause vibration or reciprocation of the drill.

Fluid under pressure is introduced into both the pneumatic device 29 below hammer 32 thereof and into the top of cylinder 13, respectively, by pipe 34 connected with device 29 and by pipe 36 connected with pipe 12 leading into cylinder 13. Valves 37 and 38 in pipes 34 and 36, respectively, control flow of fluid therethrough; and both pipes 34 and 36 are connected by T-joint 39 with common supply pipe 41 in turn connected with a suitable source of pneumatic pressure (not shown).

In operation, the pneumatic pressure causes rapid reciprocation of hammer 32 which in turn strikes dolly 27 intermittently, thus imparting a rapid series of sudden impacts to the drill to

cause vibration or endwise reciprocation thereof with consequent dislodging, by inertia, of clogged material in drill passage 2; the dislodged material escaping through passage 31 in dolly 27. At the same time, inasmuch as fluid is introduced into cylinder 13 above anvil or piston 16, pressure is applied thereto to hold the drill firmly against dolly 27 and to provide air cushioning means acting in opposition to the impacts imparted to the drill by hammer 32. Some of the fluid introduced into cylinder 13 passes through passage 19 in anvil 16, and flows into passage 2 of the drill, to aid in effecting removal of material from passage 2. Also, passage 19 serves as a bleed hole to allow anvil 16 to be readily moved upwardly in cylinder 13 when the drill is first inserted therein and the fluid pressure is shut off.

In order to lubricate the parts, if necessary, a lubricant pipe 42, connected to a suitable lubricant source, is in turn connected to pipe 41. When lubrication is desired, a suitable valve 43 connected in pipe 42 can be opened.

Although in the preferred construction, the vibrating hammer is of the pneumatic type, it is apparent that any other type of operating means for vibrating or reciprocating the drill can be employed. For example, a mechanically, hydraulically or magnetically operated hammer can be utilized.

In place of the fluid or air cushion for yieldingly resisting movement of anvil 16, a spring type of cushioning means can be employed as is illustrated in Figure 4. In the construction of Figure 4, an apertured shoulder 51 is provided in cylinder 13'; and a spring 52 is interposed between shoulder 51 and slidably mounted anvil 16' which is similar in construction to anvil 16.

I claim:

1. An apparatus for cleaning a hollow elongated member comprising a cylinder adapted to receive one end portion of said elongated member, a supporting member for the opposite end portion of said elongated member, a fluid operated hammer for intermittently striking said supporting member, and means for introducing fluid into said cylinder.

2. An apparatus for cleaning a tool having a passage comprising a supporting member for said tool and having a passage with which said tool passage is adapted to register, and means for effecting vibratory movement of said tool.

3. An apparatus for cleaning a tool having a passage comprising a supporting member for said tool and having a passage with which said tool passage is adapted to register, and means for striking said supporting member intermittently.

4. An apparatus for cleaning a hollow drill having a drill bit end comprising a cylinder adapted to slidably receive said drill, means for cushioning endwise movement of the drill in one direction, a dolly shaped to support the drill bit, a hammer for striking said dolly to move said drill against the action of said cushioning means, and actuating means for said hammer.

5. An apparatus for cleaning a hollow drill comprising a cylinder, a member for receiving an end of said drill and slidably mounted in said cylinder, supporting means for an opposite end of said drill, means for moving said supporting means intermittently in one direction, and means acting against said member for cushioning said movement.

6. An apparatus for cleaning a hollow drill comprising a cylinder, a member for receiving an end of said drill and slidably mounted in said

cylinder, supporting means for an opposite end of said drill, means for moving said supporting means intermittently in one direction, and fluid pressure means acting against said member for cushioning said movement, said member having a passage therethrough adapted to allow said fluid to flow into said drill.

5 7. An apparatus for cleaning a hollow drill comprising a cylinder, a member for receiving an end of said drill and slidably mounted in said cylinder, said member having a passage extending therethrough, and means for imparting reciprocatory movement to said drill.

10 8. An apparatus for cleaning a hollow drill comprising a frame, a cylinder adapted to receive an end portion of said drill, means supported by said frame for effecting reciprocatory movement of said drill, and means mounting said cylinder for swinging movement on said frame to provide 15 for insertion or removal of the drill.

15 9. An apparatus for cleaning a hollow drill comprising a frame, a cylinder adapted to receive an end portion of said drill, means supported by said frame for effecting reciprocatory movement 20 of said drill, means mounting said cylinder for swinging movement on said frame to provide for insertion or removal of the drill, and means for holding the cylinder against said swinging movement during the time the drill is being reciprocated.

25 10. In an apparatus for cleaning a member

30 having an axially extending passage, a tube, means for supporting said member for endwise movement with a portion of said member within said tube, means for effecting endwise vibratory movement of said member, a frame, and means 5 for movably supporting said tube on said frame to enable insertion or removal of said member.

11. In an apparatus of the character described, a tube, a member for engaging an elongated article having a longitudinal passage to be cleaned, 10 said member being movably mounted in said tube, and engageable with an end of said article, and having a passage therethrough adapted to register with the passage in said article, means 15 for introducing fluid to the end portion of said tube adjacent said end of said article, and through the passage of said member and into the passage of said article, and means for vibrating said article.

12. In an apparatus of the class described, 20 spaced members adapted to engage opposite portions of an article having a passage, each of said members having an aperture adapted to register with said passage, vibrating means acting against one of said members, and means including a tube 25 in which another of said members is movably mounted for introducing fluid through the apertures in said members and through the passage in said article.
